UNITED STATES PATENT OFFICE.

THURE E. DAHL, OF NEW YORK, N. Y.

DESIGN FOR A CHANDELIER.

61,132.

Specification for Design. Patented June 27, 1922.

Application filed May 31, 1921. Serial No. 473,921. Term of patent 7 years.

To all whom it may concern:

Be it known that I, THURE E. DAHL, a subject of the King of Sweden, residing at New York, in the county of New York and State of New York, in the United States of America, have invented a new, original, and ornamental Design for a Chandelier, of which the following is a specification, ref-

erence being had to the accompanying drawing, forming part thereof.

The figure is a perspective view of a chandelier, showing my new design.

I claim:

The ornamental design for a chandelier, as shown.

THURE E. DAHL.
